UNITED STATES PATENT OFFICE

CHARLES R. HULTGREN, OF CHICAGO, ILLINOIS, ASSIGNOR TO S. KARPEN & BROS., OF CHICAGO, ILLINOIS, A CORPORATION OF WEST VIRGINIA

REVERSIBLE SEAT OR CHAIR

Application filed December 10, 1928. Serial No. 324,933.

This invention relates particularly to a type of chair construction conveniently adapted for use in a railway coach, for example, where it is, at times, desirable to reverse the position of the front of the seat. The primary object is to provide an improved structure of such character as to enable the chair (for example, a double seat) to be reversed, or otherwise positioned, with facility.

The invention is illustrated in the accompanying drawings, in which:—

Fig. 1 is a side elevational view of the chair; Fig. 2, a detailed section taken on the line 2 of Fig. 1, showing the mechanism connecting the base to the seat structure; Fig. 3, a detail showing the position taken by the connecting mechanism when the chair is turned in a clockwise direction 90 degrees from the position shown in Fig. 2; Fig. 4, a detail taken on line 4—4 of Fig. 2, showing the shifting mechanism; Fig. 5, a detail taken on line 5 of Fig. 2, showing the lower portion of the seat post and the guide mechanism co-operating therewith; Fig. 6, an enlarged section through the base showing a modified form of shifting mechanism; Fig. 7, a detail taken on line 7—7 of Fig. 6, showing a plan of the shifting mechanism, and Fig. 8, a detail showing a second modified form of shifting mechanism, the section being taken upon a plane corresponding to that of Fig. 4.

The chair comprises a base 1, a seat portion 2 surmounting the base, a back 3, and side arms 4. The seat may be of any desired construction. For purposes of illustration the ordinary double seat commonly used in passenger coaches will be taken as a typical example of a convenient application of the novel type of connecting mechanism.

The base of the chair comprises a top wall 11, which may be of heavy sheet metal construction; an inner wall 12 spaced below the top wall; and a perimetral wall 13, the base portion of which is flared outwardly at 14 to provide a bearing flange which may be secured to the floor by screws passing through the perforations 15. The wall 13 may be struck inwardly at 13^a, and inner plate 12 which is inserted from the open bottom end of the base, is spot-welded as shown at 16.

The base portion of the seat structure is provided with a pair of diagonal cross arms 5, secured to the seat structure by means of the screws 6. If desired, a solid plate may be used instead of this cross arm type of base plate construction. The seat structure is pivotally mounted on the base by means of the post or depending stud 7, which is connected to the base portion of the seat frame through the medium of a key 8 and a disk member 9. The disk 9 is secured by the rivets 10 to the cross-bars 5.

To permit turning of the chair, it is necessary to provide for a shifting of the seat structure on the base to afford a clearance between the corners of the seat and the side wall of the car. For example, in the position of the chair shown in Fig. 1, assuming the chair is facing the front of the car, and the side wall of the car is adjacent the left end of the seat, it will be apparent that in turning the seat in a clockwise direction the rear left corner of the seat will strike the side wall of the car if the seat structure cannot shift on the base towards the center aisle of the car.

To provide for this shifting movement of the seat structure upon the base, I provide in the plate 12 a cam slot 17, into which depends a roller 18 carried on the end of a throw arm 19 which is, in turn, keyed to the post 7. Each of the plates 11 and 12 is provided with a guide slot, the slot in plate 11 being shown at 20 and that in plate 12 at 21. These slots are in vertical alignment with each other and extend parallel to the long axis of the seat. As the seat is turned in a clockwise direction from the position shown in Fig. 1, the roller 18 moves along cam slot 17, throwing the post 7 laterally along the guide slots 20 and 21 in the plates 11 and 12, respectively. It will be clear from Figs. 2 and 4 that guide slots 20 and 21 are in axial alignment with the direction of lateral movement of post 7, and that cam slot 17 is at right angles thereto. Hence during the turning operation the seat is free to shift laterally away from the car wall.

It is desirable to provide mechanism which will allow a free turning and shifting of the

seat structure upon the base, and which will also retain the same in locked position in either the forward or reversed position. For this purpose I provide a foot treadle 22, pivotally mounted in a yoke 23 which is secured by the stud 24 to a cross bar 25. The bar 25 is parallel to plates 11 and 12 and extends between the sides of the perimetral wall 13 of the base. The inner end of the treadle 22 is 10 pivotally connected to a vertical plunger member 26, which is adapted to move vertically through an aperture 27 in cross bar 25. The top surface of plunger 26 normally engages the bottom end of post 7. Plunger member 26 reciprocates in a bushing 26^a which screws into the under side of bar 25. This bushing is notched to receive the treadle as shown at 26^b in Figs. 2 and 3.

The bar 25 is provided with a groove 28 which serves as a guide for the lower end of post 7, the latter being rounded as shown to fit the groove. The detail shown in Fig. 5 clearly shows the relation between these several parts. When treadle 22 is depressed, 25 the plunger member 26 moves vertically through aperture 27, lifting post 7 and the seat superstructure mounted thereon, thereby permitting shifting or lateral movement of the post along the guide slots 20 and 21 30 and guide groove 28 upon a forcible turning of the seat superstructure. The top surface of plunger member 26 is approximately flat along its left edge, referred to Fig. 2, and rises to a tapered edge at the right, thus affording a surface which conforms in general outline to one side of the curved or rounded lower end of post 7. This upstanding portion of the top surface serves as a stop when the post approaches the limiting position 40 shown in Fig. 2. When the limiting position is reached, the seat structure may be lowered into the position shown in Fig. 2 by removing the foot from treadle 22.

When the chair is turned in a clockwise direction into a position 90 degrees from that shown in Fig. 1, the post 7 will have moved to the left to the position shown in Fig. 3. When the chair is turned in a clockwise direction through an additional 90 degrees 50 from the position shown in Fig. 3, post 7 is again immediately over the hole 27 in cross bar 25, and upon lowering plunger member 26 it is free to fall back to normal position.

An auxiliary locking mechanism may be 55 provided in the form of a boss 30 secured to top wall 11 of the base. Corresponding sockets or holes 30^a and 30^b, disposed at an angle of 180 degrees from each other, are positioned in bars 5 immediately above boss 30. As the 60 seat structure is lowered the boss comes into engagement with one or the other of the sockets to prevent further turning. The locking action afforded between the lower end of post 7 and the aperture 27 is probably sufficient in most cases.

A heavy coiled spring 31 encircles post 7 between the plates 11 and 12 of the base. The lower end of this spring extends against the throw arm 19 and the upper end presses against a bearing plate member 32. A series of ball bearings 33, carried by plate 32, facilitates turning of the seat structure on the base. The bearing plate 32 is at all times held adjacent the underside of plate 11 through the action of this spring. The ball bearings 75 are mounted in a socket container so as not to fall out when turned into a position directly below slot 20.

When the seat structure is raised by depressing the treadle 22 preparatory to turning, the lower bearing plate 34, which is keyed to post 7, is brought into contact with the underside of wall 12, thereby affording a bearing area which prevents tilting of the seat upon the base during the turning operation.

The operation of the turning and shifting mechanism is substantially as follows; assuming the seat is in the forward position shown in Fig. 1, the car wall being adjacent the left end of the seat. Treadle 22 is first depressed to raise pivot post 7 and the seat superstructure secured thereto. Upon forcible turning of the seat in a clockwise direction, the roller 18 follows cam slot 17, which in turn, through throw arm 19, shifts the post 7 laterally along guide slots 20 and 21 and guide groove 28. A clearance is thus afforded between the seat and the car wall. After a turning of 90 degrees the throw arm 19 100 will have shifted post 7 to the left end of slots 20 and 21 as shown in Fig. 3. When the reversed position is reached, that is 180 degrees from that shown in Fig. 1, post 7 will have again moved to the right and into 105 alignment with aperture 27. The seat structure is then free to be lowered into locked position. A repetition of this cycle in the reverse direction, that is turning the seat in a counterclockwise direction, will restore the 110 chair to the forward position.

Figs. 6 and 7 show a slight modification of the throw arm construction. In this modification the throw arm 42 is actuated by the link 35. One end of the link is pivotally connected to the arm 36, which in turn is pivotally connected at 37 to throw arm 42. The other end of the link is pivotally connected to a yoke 38 which is movably secured to a boss 39 on base plate 12. When the treadle 22 is depressed post 7 is raised, the arm 42 moving therewith, and as the seat structure is turned a thrust is imparted through the link 35 to the arm 42. This effects a lateral shifting of the seat structure much as in the manner already described in connection with Figs. 1-5.

Fig. 8 shows a second modification of the throw arm mechanism. In this form throw arm 43 is provided at its free end with a de-

pending roller 40 which engages a slot 41 in plate 12. This form is very similar to the type shown in Fig. 4, the essential difference being that the cam slot 41 is not curved or arc-shaped, but extends throughout its length at right angles to the slot 21 to form therewith a T-slot. The operation is similar to that shown in Fig. 4.

This invention is a modification of the invention shown in my application Serial No. 326,123, filed Dec. 14, 1928, which matured into Patent No. 1,803,063 dated April 28, 1931.

The foregoing detailed description has been given for clearness of understanding only and no unnecessary limitations should be understood therefrom, but the appended claims should be construed as broadly as permissible in view of the prior art.

What I regard as new, and desire to secure by Letters Patent, is:

1. In a chair of the character described provided with a base and a seat structure adapted to turn upon the base, connecting means between the base and seat structure permitting a substantially 180 degree turning of the seat structure upon the base and serving to effect a lateral shifting of the seat relative to the base during said turning, said connecting means including a pivot post secured to the seat structure, a throw-arm mounted to turn with said pivot post, a roller depending from said throw-arm, and a base plate provided with a cam slot positioned to engage said depending roller.

2. In a chair of the character described provided with a base and a seat structure adapted to turn upon the base, connecting means between the base and said seat structure permitting a substantially 180 degree turning of the seat structure on the base and serving to effect the lateral shifting of the seat relative to the base during said turning, said connecting means including a pivot post secured to the seat structure, a throw-arm mounted to turn with said pivot post, a roller depending from said throw-arm, a base plate provided with a cam slot positioned to engage said depending roller, and locking means for securing the seat against said turning and shifting movements.

3. In a chair of the character described provided with a pivot post adapted to permit turning of the seat structure upon the base, connecting means between the seat and base permitting substantially 180 degree turning of the seat structure on the base and serving to effect a lateral shifting of the seat in the operation of turning the same on the base, and locking means for holding said seat structure against said turning and shifting movements, said locking means comprising a base plate provided with a retaining aperture positioned to engage the lower end of the pivot post, a treadle pivoted to the base, and a

plunger member carried by said treadle and serving to raise said pivot post out of said retaining aperture.

4. The device as claimed in claim 3, further characterized by additional locking means positioned between the top wall of the base and the base portion of the seat structure.

5. A chair of the character described comprising a base, said base including a top wall provided with a guide slot, an inner wall below and spaced from the top wall and provided with a guide slot, and a cross-bar mounted below and parallel to said inner wall and provided with a guide groove; a seat structure mounted upon said base; and connecting means between said base and said seat structure permitting shifting and turning of the seat structure upon the base, said means including a pivot post secured to the seat structure and depending through said guide slots, the lower end of said post being adapted to engage said guide groove, and a throw-arm adapted to reciprocate said post along said guide slots and guide groove upon forcible turning of the seat structure through an arc of substantially 180 degrees.

6. A chair of the character described comprising a base, said base including a top wall provided with a guide slot, an inner wall below and spaced from the top wall and provided with a guide slot, and a cross bar spaced below and parallel to said inner wall and provided with a guide groove; a seat structure mounted upon said base; connecting means between said base and seat structure permitting shifting and turning of the seat structure on the base, said means including a pivot post secured to the seat structure and depending through said guide slots, the lower end of said post normally resting in a retaining aperture in said cross bar, and a throw-arm adapted to reciprocate said post along said guide slots and guide groove upon forcible turning of the seat structure through an arc of substantially 180 degrees; and locking means for holding the seat structure against said turning and shifting movements, said means including a treadle pivoted to said base and provided with a plunger member positioned to raise said post into said guide groove preparatory to turning the seat on the base.

7. A chair of the character described comprising a base, a seat structure, pivotal connecting means between the base and said seat structure, and means permitting a substantially 180 degree turning of the seat structure upon the base and serving to shift the seat structure laterally on the base during said turning, said means comprising a top plate provided with a guide slot, an inner plate spaced below said top plate and provided with a cam slot and a guide slot in alignment with said first mentioned guide

slot, and a throw-arm carried by said pivotal connecting means and provided at its free end with a depending roller adapted to ride in said cam slot.

5 8. In a chair of the character described comprising a base, a seat structure mounted upon the base, and pivotal connecting means between said base and seat structure; means for shifting said structure upon the base
10 from a normal central position to a limiting lateral position and back to said central position during a half revolution of said seat structure, said shifting means comprising a throw-arm adapted to turn with said pivotal connecting means, a horizontal plate secured to the base, said plate being provided with a guide slot axial with the line of lateral movement and a cam slot positioned at right angles to said guide slot, and a guide member depending from the free end of said throw-arm into said cam slot.

25 9. A chair of the character described comprising a base provided with a top bearing wall and a lower bearing wall spaced from said top wall, a seat structure mounted upon said base, a pivot post carried by said structure and depending into the base, a throw-arm carried by said pivot post and adapted to reciprocate the seat structure laterally on
30 the base during a half revolution of the same on the base, a cross-bar secured to the base below said lower bearing wall and provided with a retaining aperture normally holding said pivot post in said lateral movement, a
35 treadle provided with an arm positioned to raise said pivot post from said retaining socket, a top bearing plate secured to said seat structure and normally engaging said top bearing wall, and a bottom bearing plate secured to said pivot post and positioned to engage said lower bearing wall during the interval of turning.

40 10. In a chair of the character described comprising a base, a seat structure mounted upon the base, and connecting means between said base and said seat structure; means for shifting said seat structure upon the base from a normal central position to a limiting lateral position and back to said central position during a half revolution of said seat structure, said shifting means comprising a throw-arm adapted to move simultaneously with said connecting means, a member secured to the base, said member being provided with a guide slot axial with the line of lateral movement and a cam slot positioned adjacent one end of said guide slot, and a guide-member extending from the free end of said throw-arm into said cam slot.

45 60 In witness whereof I have hereunto set my hand this 27th day of November, 1928.

CHARLES R. HULTGREN.
